(57) **CLAIM**

The ornamental design for woven seamless pants, as shown and described.

DESCRIPTION

FIG. 1 is a front, right side perspective view of woven seamless pants according to our new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a cross-sectional view of the right inseam of the woven seamless pants taken from line 6-6 in the view of FIG. 4.

The applied stippling technique and fine lines in the drawings depict an applied shading technique that defines the contours of the woven seamless pants and do not reflect a particular surface ornamentation or material. The dash-dot broken lines in FIGS. 1-6 illustrate waist-to-crotch and ankle portions of the woven seamless pants which form no part of the claimed design, while the dash-dot-dot broken lines in FIGS. 1-6 define boundary lines to the claimed design and form no part thereof. The appearance of any portion of the article between the dash-dot-dot break lines forms no part of the claimed design.
